(57) **CLAIM**

The ornamental design for an electric mosquito swatter, as shown and described.

DESCRIPTION

FIG. 1 is a front, right side and top perspective view of an electric mosquito swatter showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an exploded front, right side and top perspective view thereof.

The dashed broken lines in the drawing depict portions of the electric mosquito swatter that form no part of the claimed design.
